UNITED STATES PATENT OFFICE.

THOMAS C. WASHINGTON, OF WASHINGTON, DISTRICT OF COLUMBIA.

PUZZLE.

Application filed March 14, 1921. Serial No. 452,043.

To all whom it may concern:

Be it known that I, THOMAS C. WASHINGTON, citizen of the United States, residing at Washington, District of Columbia, have 5 invented certain new and useful Improvements in Puzzles, of which the following is a specification.

This invention relates to improvements in puzzles and more particularly to a puzzle 10 wherein the object is to cause a series of movable elements to be moved, in sequence, through different ways and means into a final container.

The principal object of the invention is to 15 provide a puzzle whose proper operation requires the exercise of both skill and patience and is so constructed whereby it may be cheaply manufactured and sold at a reasonably low cost.

20 A further object of the invention is to provide a puzzle as above described wherein the body and in fact all parts thereof excepting the movable elements may be formed in an integral piece of material 25 such as papier mâché or other material that may be so stamped and molded.

Various other objects and advantages of my invention will become apparent during the continuance of the following description.

In the drawings:

Figure 1 is a view in top plan showing my invention as in its preferred embodiment.

35 Figure 2 is a view in transverse cross section taken through the body of the puzzle.

The body portion of the puzzle comprises an outer rim 10 which carries an inwardly projecting bottom portion 11, a slanting 40 connecting portion 12 and a raised center portion 13. This construction provides an outer circular channel or passageway 14 level with the bottom of the rim 10 as clearly shown in the drawing. This channel 45 or passageway receives the movable elements or balls 15 which are numbered 1, 2, 3 and 4 respectively when it is desired to begin the operation of the puzzle.

The raised center portion 13 is provided 50 with a concentric circular rim 16 which has an opening 17 on one side and which divides the center portion into an outer channel 18 and a container 19. In order to establish communication between the channel 14 and 55 the channel 18 and thus enable the balls 15 to be moved from the channel 14 to the

channel 18 thence through the opening 17 into the container portion 16, the raised intermediate part 12 is provided with a series of spaced by-passages 20, 21, 22 and 23 that 60 are spaced at substantially 90 degrees from each other and so that the by-passage 20 is aligned with the opening 17 of the rim 16. These by-passages open flush with the bottom of the passageway 11 and the passageway 18 so that when the puzzle is tilted to a proper degree, the operator may cause one of the balls to roll through one of the by-passages into the passageway 18. The operator may then cause the ball to roll around 70 the passage 18 and through the opening 17 into the container 19. The container 19 is provided with a recess 24 of graduated depth that terminates in substantial alignment with the by-passages 21 and 22. The 75 purpose of this particular arrangement will be hereinafter described. It will also be noticed that the by-passages are number 1, 2, 3 and 4 respectively to correspond with the numbers of the balls 15. 80

The object of the puzzle is to get the balls 15 from the passage 14 to the container 19 through the proper by-passages and in proper sequence. In other words, ball #1 is caused to roll through the by-passage marked #1 and designated by the numeral 20, across the passage 18 into the container 19. Getting the first ball into the container is comparatively easy by reason of the fact that the by-passage 20 is aligned 90 with the opening 17 through which the ball has to pass to get into the container. Ball #1 having found its seat in the recess 24, ball #2 is then rolled through the by-passage marked #2, around the passage 18 until 95 it enters the container through the opening 17. Inasmuch as the ball #1 is seated in the recess 24 it will not be dislodged during this manipulation unless the operator tilts the body too much in causing the ball to 100 roll to its final destination. After the first three balls have been gotten into the container the most difficult part of the operation begins. However by properly manipulating and tilting the body, ball #4 may be 105 gotten into the container without dislodging the remaining three.

What is claimed is:

A puzzle of the character described comprising a body portion having a circular 110 channel way, a raised center portion concentric to said channel, radial channels

leading from said first named channel to said center portion, means dividing said center portion into a circular channel concentric to said first named channel and open 5 to said radial channels and a container open to said last named channel at a point in alignment with certain of said radial channels, said center portion provided with a

recess offset with respect to the opening between the same and said last named channel, 10 and a series of movable elements to be operated in connection therewith substantially as described.

In testimony whereof I affix my signature.

THOS. C. WASHINGTON.
